(57) **CLAIM**

We claim the ornamental design for a housing for fan, as shown and described.

DESCRIPTION

FIG. 1 is a front elevational view of a housing for fan showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is an enlarged front elevational view taken along line 7-7 in FIG. 1;

FIG. 8 is an enlarged top plan view taken along line 8-8 in FIG. 5;

FIG. 9 is an enlarged bottom plan view taken along line 9-9 in FIG. 6;

FIG. 10 is a top perspective view thereof;

FIG. 11 is a bottom perspective view thereof;

FIG. 12 is an enlarged top perspective view taken along line 12-12 in FIG. 10;

FIG. 13 is an enlarged bottom perspective view taken along line 13-13 in FIG. 11;

FIG. 14 is a top perspective view shown in an alternate environment;

FIG. 15 is a bottom perspective view shown in an alternate environment;

FIG. 16 is an enlarged top perspective view taken along line 16-16 in FIG. 14; and,

FIG. 17 is an enlarged bottom perspective view taken along line 17-17 in FIG. 15.

The broken line showing of structural elements is included for the purpose of illustrating portions of the housing for fan and forms no part of the claimed design.

The wiring depicted by means of broken lines in FIGS. 14 through 17 is included for the purpose of illustrating environmental structure and forms no part of the claimed design.
